UNITED STATES PATENT OFFICE

155,633

DESIGN FOR A CHARM OR SIMILAR ARTICLE

Frida Schneebaum, New York, N. Y.

Application September 1, 1948, Serial No. 148,411

Term of patent 3½ years

(Cl. D45—17)

To all whom it may concern:

Be it known that I, Frida Schneebaum, a citizen of the United States, residing at New York, in the county and State of New York, have invented a new, original, and ornamental Design for a Charm or Similar Article, of which the following is a specification, reference being made to the accompanying drawing, forming a part thereof.

In the drawing:

Fig. 2 is a side elevational view of the charm; and

I claim:

The ornamental design for a charm or similar article, as shown.

FRIDA SCHNEEBAUM.
